Primary Examiner — Sanjeev Paul

(57) **CLAIM**

The ornamental design for a multi layer pillow, as shown and described.

DESCRIPTION

The patent or application file contains at least one drawing executed in color. Copies of this patent or patent application publication with color drawing(s) will be provided by the Office upon request and payment of the necessary fee.

1. Multi layer pillow

3. Multi layer pillow

1.1 : Bottom Layer

1.2 : Front

1.3 : Layer 1

1.4 : Layer 2

1.5 : Perspective

3.1 : Perspective

3.2 : Front

3.3 : Intermediate Layer

3.4 : Bottom Layer

A multi layer pillow comprised of four layers: a top layer, two intermediate layers and a bottom layer.
